UNITED STATES PATENT OFFICE.

JAMES MORRISON, JR., OF NEW YORK, N. Y.

LATH.

SPECIFICATION forming part of Letters Patent No. 311,666, dated February 3, 1885.

Application filed December 13, 1884. (No model.)

To all whom it may concern:

Be it known that I, JAMES MORRISON, Jr., of New York, in the county of New York and State of New York, have invented a new and 5 Improved Lath, of which the following is a full, clear, and exact description.

This invention relates to an improved web of lath; and it consists, principally, in attaching lath to a flexible backing, to facilitate 10 the application of the lath to the joists of the building, and also to cause the plaster to key 15 closely to the lath, thereby effecting a saving in mortar and producing a better and firmer wall.

Reference is to be had to the accompanying 15 drawings, forming part of this specification, in which similar letters of reference indicate corresponding parts in both the figures.

Figure 1 is a front elevation of my invention, part of the lath being covered with plaster. Fig. 2 is a sectional elevation of the same, taken on the line *x x* of Fig. 1.

A represents the backing, and B the lath. The backing A is by preference flexible, so 20 that the lath may be rolled into bundles to facilitate handling, and the backing A is by preference composed of tarred paper or felt. The lath-sticks B are secured across the backing A parallel with each other, and are by 25 preference secured to the backing by means

of tar or other adhesive material. The edges of the lath-sticks B are beveled, as shown at *a*, so as to form a kind of dovetail for the "key" of the plaster C, as shown clearly in Fig. 2, thus causing the plaster to adhere to 35 the lath with great firmness. The lath, being attached to the backing A, can be applied to the joists and nailed with great rapidity, and the backing, besides serving to prevent the plaster, when applied, from passing back 40 of the lath, also serves as a good "deafening" for the wall, and it causes the plaster to key both with the upper and the lower lath, as shown in Fig. 2, so that the wall is thus made very firm with the minimum quantity 45 of plaster.

Having thus described my invention, what I claim as new, and desire to secure by Letters Patent, is—

1. As a new article of manufacture, a web 50 of lath composed of the backing A and lath-sticks B, secured to the backing, substantially as described.

2. The lath-sticks B, secured to the backing A, and beveled at their edges, substantially as and for the purpose set forth.

JAMES MORRISON, JR.
